(57) **CLAIM**

We claim the ornamental design for a game machine, as
shown and described.

DESCRIPTION

FIG. 1 is a first perspective view of a new design of a game
machine;

FIG. 2 is a front view of the new design of a game machine;
FIG. 3 is a second perspective view of the new design of a
game machine, shown enlarged and broken away for ease of
illustration;

FIG. 4 is a third perspective view of the new design of a game
machine;

FIG. 5 is a right side elevation view of the new design of a
game machine;

FIG. 6 is a left side elevation view of the new design of a game
machine;

FIG. 5 is a top view of the new design of a game machine;
FIG. 7 is a second front view of the new design of a game
machine; and,

FIG. 8 is a rear view of the new design of a game machine.
The broken lines shown in the figures are for illustrative
purposes only and form no part of the claimed design.

1 Claim, 7 Drawing Sheets
